UNITED STATES PATENT OFFICE.

THOMAS MIDGLEY, SR., OF HAMPDEN, MASSACHUSETTS, ASSIGNOR TO THE FISK RUBBER COMPANY, OF CHICOPEE FALLS, MASSACHUSETTS, A CORPORATION OF MASSACHUSETTS.

COLLAPSIBLE CORE.

1,389,892.

Specification of Letters Patent. Patented Sept. 6, 1921.

Application filed March 19, 1919, Serial No. 283,534. Renewed February 2, 1921. Serial No. 441,929.

To all whom it may concern:

Be it known that THOMAS MIDGLEY, Sr., a citizen of the United States, residing at Hampden, in the county of Hampden, Massachusetts, has invented certain new and useful Improvements in Collapsible Cores, of which the following is a specification.

This invention relates to cores and, more particularly, to collapsible cores designed for use in the manufacture of pneumatic tire casings, the object of the invention being to provide a structure of this nature to which a heating medium may be applied.

Another object of the invention is to provide a joint structure between the various core sections which enables free circulation of a heating medium without the necessity of resorting to the use of awkward and bothersome bypass structures. In other words, the invention aims to so form the joining portions of the various core sections that their mere assemblage produces a continuous heating connection throughout the several sections of the core.

Other advantages will be apparent from the description herewith.

The preferred embodiment of my invention is shown in the accompanying sheets of drawings wherein similar characters of reference designate corresponding parts and wherein,

Figure 1 is a view showing my improved type of core in its assembled relation prior to the application of the tire parts thereon,

Fig. 2 is an enlarged cross-section taken on line 2—8 of Fig. 1,

Fig. 3 is a detailed sectional view showing the manner in which the abutting ends of the core sections register and are made tight for the passages between the interiors of adjacent sections, and

Fig. 4 is a slightly modified form of the invention.

As shown in Fig. 1, the core is made of four sections, the section 1 constituting what is known as the key piece and the remaining sections 2, 3 and 4 being of such form as to complete the annulus. The abutting ends of these various sections are constructed so

that when they are assembled, a circumferential separation between ends will be prevented by means of the spring ring 5 which is positioned therein and held in such position by means of the key 6. In other

words, these abutting ends are provided with 5 interengaging offset portions which function as hooks of plug and socket form such that their displacement circumferentially or outwardly is prevented by the expansion of the ring 5 into position all as explained in 60 my co-pending application filed of even date Serial Number 283,533.

As is customary, the abutting ends of each of the sections are faced with plates 7 and 8 and these plates are also formed to present 65 the plug and socket construction shown. The interior of each of the various core sections is hollowed out as shown at 9 and the various core sections are in communication with each other by means of the conduits 10 and 11, each of which is so located to pass centrally through the plug and socket structure. These plugs and sockets are also tapered slightly to closely interfit and in fact the parts are made to exactly 75 fit when they are assembled to form a steam tight union. In this manner, the passages 10 and 11 of each of the three joints equipped with them will always be in registry while the parts are assembled. In order to prevent 80 the possible escape of any of the heating medium I have also provided each plug and socket with a semi-circular gasket receiving opening in which the gasket 12 may be inserted and which gasket firmly 85

seals the section ends against the possible escape of any of the heating medium when the parts are wedged together. As is evident from Fig. 1, only three of the joints are provided with these registering 90

passages, it being unnecessary to provide the fourth one with the same inasmuch as the heating medium may be introduced into the section 1 by means of the nipple shown at 13 and this heating medium then circulated 95 throughout the core and withdrawn through the nipple shown at 14 as being connected with the section 3. It will of course be understood that the spring ring 5 is suitably slotted to permit its ready application to 100 accommodate these nipples 13 and 14.

From the foregoing description, taken in connection with the accompanying sheets of drawings, it will be apparent that I have provided a type of structure which is self 105 alining in so far as the continuity of the passages 10 and 11 is concerned. Further, no unnecessary structure is utilized in order

to permit the complete circulation of a heating medium throughout the interior of the entire core.

In the preferred embodiment of my invention the core sections, as above described, are preferably heated by the introduction of steam, or other heated fluid, into the hollow interiors of the assembled sections. It is obvious that the core as a whole may be heated in many other different ways, without parting from the spirit of the invention. Therefore, a modification has been shown in Fig. 4 of the drawing, wherein the core consists of the usual interfitting sections 15, and 10 which are held in assembled relation by means of the expansible ring structure 16, and in this instance the core sections are uniformly heated by the application of an electrical current, which may be accomplished 15 by means of the terminals 17. By associating electric conductors 18 with said terminals, current may be supplied to the entire core body, in order that the latter may be heated in a uniform manner and to the required temperature.

What I claim is:

1. In a collapsible core, a plurality of core sections shaped to form an annulus, means whereby said sections may be heated including a connection for the heating medium adapted to be established through the abutting ends of the sections when the latter are assembled, and means for holding the sections in assembled relation.
- 35 2. A collapsible core of the type having a plurality of sections forming an annulus when in assembled relation and being provided with interengaging portions on their abutting surfaces, characterized by that construction of said interengaging portions in which they provide a connection for a heating medium between certain of said sections.
- 40 3. In a collapsible core, a plurality of core sections shaped to form an annulus, the interior of said sections being of hollow form, means whereby communication may be established between at least certain of said sec-

tions through their abutting ends, means whereby a heating medium may be introduced to and withdrawn from the interior of the assemblage, and means whereby said sections are held assembled.

4. In a collapsible core, a plurality of core sections shaped to form an annulus, the interior of said sections being of hollow form, the abutting ends of at least certain of said sections being provided with co-operating plug and socket formations, said last named sections having communicating passages leading through said plug and socket formations, means whereby a heating medium may be introduced to and withdrawn from the interior of the assemblage, and means whereby said sections are held assembled.

5. In a collapsible core, a plurality of core sections shaped to form an annulus, the interior of said sections being of hollow form, the abutting ends of each pair of sections except one having communicating passages between them, means for introducing a heating medium to one core section having a closed end, means for withdrawing the heating medium from the other section having a closed end, and means whereby said sections are held assembled.

6. A sectional hollow core having abutting ends with passages for interior connection between the hollow sections, the portions of said passages where they pass through abutting ends of the sections having a substantial radial direction will respect to the core.

7. A sectional hollow core having abutting ends with passages for interior connection between the hollow sections, said passages making a sharp bend at their middle portions so as to pass through the joints of the core in a radial direction whereby the expansion of sections into place will not disturb the alignment of passages between sections.

In testimony whereof I affix my signature.

THOMAS MIDGLEY, SR.
